UNITED STATES PATENT OFFICE.

JOSEPH H. LEHMAN, OF HASBROUCK HEIGHTS, NEW JERSEY.

IGNITION APPARATUS.

Application filed February 25, 1922. Serial No. 539,093.

This invention is an improvement in apparatus for controlling electric circuits, particularly those of ignition apparatus for multiple-cylinder internal combustion engines.

- 5 A preferred embodiment is used as a timer for the primary or low tension current, and a distributor for the secondary or high tension current, and involves certain improvements over the constructions shown and 10 broadly claimed in my prior Patents 1,415,369 and 1,415,370, granted May 9, 1922. The current reversing feature is an improvement on that broadly claimed in my prior Patent 1,251,249 issued December 25th, 1917.
- 15 One important object of my present invention is to provide means whereby the apparatus may be readily adapted for either a double or a single ignition system by the addition or removal of supplementary parts 20 which may be so designed as to be applied to timers and distributor for single ignition systems now on the market. Another important object is to provide means whereby operating mechanism of the make-and-break 25 devices for the primary circuit may be assembled for rotation in either direction, depending upon the direction of the drive from the engine crank shaft. Another object is to increase the current flow and effectiveness of 30 the spark thus better adapting the apparatus for use with high speed engines. There are various other important features which will be pointed out in connection with a description of a preferred embodiment of the invention, many of these features having for their 35 object the reduction of cost, simplification of construction, ease of assembly, adjustment, and repair, and reduction of wear.

In the accompanying drawings:—

- 40 Fig. 1 is a central longitudinal section through a device constructed in accordance with my invention.

Fig. 2 is a top plan view of the lower portion of the casing, a portion being broken away, and the timer and distributor heads being removed.

Fig. 3 is a plan view of the timer head, the line 1—1 thereon indicating the section on which Fig. 1 is taken.

50 Fig. 4 is an edge view of the head shown in Fig. 3.

Fig. 5 is an inverted plan view of the head shown in Fig. 3.

Fig. 6 is a sectional detail on the line 6—6 of Fig. 3. 55

Fig. 7 is a side elevation of one brush holder.

Fig. 8 is a side elevation of the other brush holder.

Fig. 9 is an end view of one of the brush 60 holders.

Fig. 10 is a perspective view of one of the collector ring sections on the timer head.

Fig. 11 is a perspective view of one of the intermediate wear pieces on the timer head. 65

Fig. 12 is a section similar to Fig. 1, but with additional parts inserted for a double ignition system.

Fig. 13 is an inverted plan view of the supplementary distributor casing section shown 70 in Fig. 12, a portion thereof being broken away.

Fig. 14 is a section on the line 14—14 of Fig. 13.

Fig. 15 is a top plan view of the upper distributor brush member. 75

Fig. 16 is a top plan view of the lower or supplementary distributor brush member.

Fig. 17 is a top plan view of a modified 80 form of timer head, and

Figs. 18 and 19 are sections on the lines 18—18 and 19—19 respectively of Fig. 17.

As illustrated in Figs. 1 to 10 inclusive, there is provided a casing within which is rotatably mounted means for intermittently 85 making and breaking the primary circuit a plurality of times during each complete revolution of the rotor, and means for distributing the secondary circuit to terminals corresponding in number to the engine cylinders 90 or spark plugs. The rotor includes a shaft 20 which may be provided with any suitable means for driving it at the desired rate of speed. I have illustrated the lower end of 95 the shaft as being provided with a helical gear 21. Rigidly secured to the shaft within the casing there is provided a timer head constructed as illustrated in detail in Figs. 3 to 6 inclusive. The head includes a metal sleeve 100 portion 22 fitting upon a portion of the shaft 20 of reduced diameter, and seating on a

shoulder 23. The body portion 24 of the timer head is formed of insulation material which may be molded, pressed or cut, to the desired form. The material commonly known as bakelite is suitable for this purpose, although other materials might be employed. Encircling the head is a metal collector ring formed of two sections 25 and 26, each substantially semi-cylindrical in form, but extending along somewhat less than 180° of the circumference of the timer head, so that the two are effectively insulated from each other. The ring section 25 has an inwardly extending lug 27 at its upper edge, imbedded within the insulation forming the body, and the ring section 26 has a similar lug 28. These lugs serve not only to effectively hold the ring sections in permanent rigid engagement with the body of the head, but also serve for the connection of operating parts, as herein-after pointed out. If desired, each ring section may have an additional lug 29 for anchoring it in the body of the head, such lug being at the lower edge of the collector ring section.

The collector ring sections are connected to the opposite terminals of the source of electrical energy as herein-after pointed out, and the head carries means for intermittently making and breaking the circuit from one collector ring section to the other. This means includes a pair of make-and-break contacts 30 and 31, the former being connected to the collector ring section 26, and the latter to the collector ring section 25. The contact 30 is carried by and adjustable in respect to a post 32 substantially parallel to the axis of rotation of the head. The post has a threaded stem portion 33 extending through the insulation head, and through an aperture in the lug 28, of the collector ring section 26. The threaded stem 33 terminates in a socket or recess in the under side of the head and receives a retaining nut, as shown particularly in Fig. 1. By tightening this nut, the upper or head portion of the stem may be rigidly clamped to the head. As the stem may be rotated about its own axis, it will be apparent that the post may be clamped with the face of the contact adjusted to the proper angle to make perfect electrical engagement with the other contact. The contact itself is carried by a screw which may be adjusted back and forth through the post and lug and locked by a nut 34.

The other contact member 31 is carried by an upturned flange or lug 35 on a bell crank lever 36. This lever is provided with a sleeve or bearing portion 37 rotatably mounted upon a post 38 carried by the head, but projecting upwardly in a direction substantially parallel to the axis of rotation of the head. This post, as shown particularly in Fig. 6, has a stem part 39 which is eccentric in respect to the body portion of the post, and which ex-

tends through the head into a recess or cavity in the under side, and is locked in position by a suitable nut 40. The post has a polygonal or other non-circular portion 41 which may be engaged by a wrench or other tool to rotate the post when the nut 40 is properly loosened. Due to the eccentricity of the stem 39, and the body portion 38 of the post, it will be apparent that such rotary movement tends to move endwise the portion of the bell crank lever carrying the contact 31. Thus the contact may be moved back and forth substantially in its own plane to get it to the properly adjusted position for perfect engagement with the face of the opposed contact 30. It will be noted that the post is not directly connected to either of the collector ring sections. The end of the bell crank lever opposite to the end carrying the contact 31, carries a projecting part 42 which may engage with a casing part in the path thereof to cause the oscillation of the lever during the rotation of the head, and to open and close the circuit at the proper time intervals. This part of the structure with which the projection 42 engages will be described more in detail herein-after. The projection is preferably formed of insulation material. For rigidly holding the projection on the upper leaf 43, the projection may be riveted between the two leaves, as shown particularly in Fig. 4, and may back up against a lug 44 integral with and bent up from the inner edge of the end portion of the body of the lever 36.

For conducting the current to the lever 36 and its contact 31, and for normally holding the contacts 30 and 31 together, I provide a leaf spring 45, one end of which is secured to the inner surface of the lug 44, at one end of the lever, and an intermediate portion of which is bent around the sleeve portion 37 at the fulcrum of the lever. A portion of the spring adjacent to its opposite end, extends through a slot in a post 46, and is rigidly secured to this post. The post 46 has a stem portion similar to the stem portions 33 and 39, and extends through the insulation head and through the lug 27 of the collector ring section 25. Thus, the current from the collector ring section 25 may pass to the collector ring section 26 by following through the following parts, lug 27, post 46, spring 45, lever 36, contacts 31 and 30, post 32, and lug 28.

As one important feature of my invention the spring 45 is so constructed as to operate in a double capacity on the bell crank lever constituting the current breaker arm. During the rotation of the interrupter head the projection 42 engages with a series of cams or projections on the interrupter housing, as herein-after set forth. The greater the speed at which the interrupter head rotates, the greater will be the force of the blow imparted to the projection 42, and there will be a ten-

- dency of the contact 31 to move to correspondingly greater distances from the contact 30. The greater the time during which these contacts are separated, the greater will be the 5 time interval of current interruption. For high speed motors it is desired that this current interruption be for as short an interval as possible, in order that the current may build up in the induction coil.
- 10 The spring 45, by reason of its engagement with the post 46, the lever, and the fulcrum of the lever, returns the contact 31 to closed current position as soon as the projection 42 is free of the obstruction in its path, during 15 normal or slow speed rotation. The spring has a terminal portion 47 extending beyond the post 46 and bent to form a stop in the path of movement of the lug or flange 35 on the lever. During normal or slow speed 20 operation the lug comes merely to this spring, does not forcibly impact against this spring, and in fact, need not even engage with it. During high speed operation, when the force of the blow against the projection 42 tends 25 to swing the breaker or interrupter arm to excessive distances, the spring stop 47 acts to limit or prevent such movement. When the movement is such as to bend the spring stop, the energy stored in such bending movement acts instantly to return the breaker arm 30 at high speed and bring the contacts together to close the circuit after the shortest possible time interval following the opening of the circuit.
- 35 The timer or interrupter head with the parts mounted as shown in Fig. 3, is intended for counter-clockwise rotation. As one important feature of my improved construction the design is such that the post and parts carried thereby may be removed, and be mounted for clockwise direction if the timer shaft of the engine in connection with which the timer is to be employed, have that direction of rotation. The lugs on the collector ring 40 sections 25 and 26, and the holes or sockets in the head are in duplicate and are symmetrical in respect to a plane (indicated by the line A—B in Fig. 5) at right angles to the axial plane between the two collector 45 ring sections. Thus the collector ring section 25 has a lug 27^a, and the collector ring section 26 has a lug 28^a. The head has recesses or sockets 33^a and 46^a extending up into the head from the under side at these lugs, 50 and into which may project the threaded stems of the posts 32 and 46. There is also provided a socket or recess 39^a, disposed on the opposite side of the line A—B in respect to the socket which receives the threaded stem 55 39 of the post 38. It will be noted that all of the parts designated by reference characters having the exponent "a" are disposed on the same chords at right angles to the line A—B as are the parts having corresponding 60 numerals without the exponent. By mount-
- ing the post 38 with its stem 39 in the recess 39^a, mounting the post 46 with its stem in the recess 46^a, and connected to the lug 27^a, and by mounting the post 32 with its stem 33 in the recess 33^a, and connected to the lug 7^a 28^a, all of the parts will be in reverse position from that shown in Fig. 3, and the head will be adapted for clockwise rotation rather than counter-clockwise rotation. With the parts so reversed, each part will be at the 75 same distance from the gaps between the collector ring sections as before.
- Preferably in the construction of the head the recesses which are not to be employed in the original assembly may terminate a slight 80 distance below the upper surface of the body of the head, so as not to be apparent from the upper surface. When it is desirable or necessary to reverse the position of the make-and-break parts, the holes may be very easily drilled the rest of the way through.
- In order that the brushes hereinafter referred to, and which engage with the collector ring sections shall not act to bridge across the gap between one section and the other, it is important that the width of the gap be greater than the width of the brush. As one important feature of my construction I provide a pair of metal inserts 48 in the body, and disposed in the gaps between the 90 ends of the collector ring sections. These have their outer surfaces in the same arc with the outer surfaces of the collector ring sections, and are of such width that there is only the minimum necessary insulation between each insert and the two collector ring sections. Thus the brush may ride from one section on to an insert, and then on to the other section, without short circuiting. The brushes always bear on metal, and at no time 100 press solely against the insulation. Thus the wear on the periphery of the head is uniform. These insertions may be firmly anchored in place in any suitable manner, as for instance, each may have a recess 49 in its inner edge 110 which forms a dove tail interlocking with the insulation at the time the latter is molded in place.
- For mounting the timer or interrupter head on the shaft 10, and at the same time 115 permit of its ready removal and circumferential adjustment, the upper end of the shaft is provided with a central longitudinal tapered recess adapted to receive a conical wedge 50. The peripheral wall of the shaft 120 is longitudinally slotted, and means are provided for moving the wedge endwise to expand or permit contraction of this portion of the shaft so as to grip or release the metal sleeve or bearing portion 22 of the head. As 125 shown, there is a central screw 51 carrying the wedge between the head thereof and a stop or shoulder, so that the wedge is moved endwise with the screw. The inner end of the screw has threaded engagement with the 130

shaft at the inner end of the socket which receives the wedge. The stop on the screw at the inner end of the wedge may be in the form of a small, split ring disposed in a peripheral groove in the screw.

In assembling the parts, the head may be slipped on to the end of the shaft into engagement with the shoulder 23, and may be rotated on the shaft to the desired position. 10 By then tightening the screw 51, the head is firmly clamped in position. This tightening action does not tend to rotate the head on the shaft, and thus accurate adjustment can be secured.

15 The casing of my improved device includes a body portion formed of sheet metal and supported by and secured to a bearing sleeve 53 which may be cast or turned from a drawn bar. This bearing sleeve has a terminal portion of reduced diameter extending into the timer head to the end of the sleeve 22 of the latter, and a peripheral flange 54 to which the sheet metal body portion is secured. This body portion includes a substantially cylindrical peripheral wall 55 for encircling the timer head, but spaced from the periphery of the latter, a bottom wall 56 secured to the flange 54 of the bearing sleeve, an outwardly extending top wall or flange 57 in a plane 20 slightly above the upper surface of the body of the timer head, and a substantially cylindrical peripheral flange 58 extending upwardly from the outer edge of the flange 57. The casing forms a cuplike chamber within 25 the wall 55 above the wall 56, and below the flange 57, and within which the timer head is mounted.

30 The flange portion 57 carries the interrupter housing which acts to intermittently engage with the projection 42 on the breaker arm, and thus effect a make-and-break of the circuit a plurality of times during the rotation of the timer head. As shown, this interrupter housing is in the form of a sheet 35 metal ring 59 having an upturned peripheral flange 60 adjacent to the flange 58 of the casing, and cooperating with the latter to form a rigid outer wall and a firm support for the casing cover. The inner edge of this sheet 40 metal ring or annulus has a plurality of upwardly extending flanges 61 spaced at equal distances apart, and corresponding in number to the number of cylinders of the engine in connection with which the timer is to be 45 employed. As illustrated, there are four of these flanges or projections 61. Thus, in the device illustrated, the breaker arm will be moved four times during a complete rotation of the timer head, and the circuit will be made 50 and broken a corresponding number of times. These flanges or projections 61 are preferably bent to present curved cam surfaces, as shown particularly in Fig. 2, so that the breaker arm projection 42 may strike the cam and ride up 55 one side and down the other. The center

portions of the surface of all of the projections 61 are preferably ground so as to be slightly concave, and all in the same arc and at the same distance from the axis of rotation of the timer head. Thus the maximum 70 distance to which the breaker arm will be moved by each cam projection will be exactly the same, in spite of any slight inaccuracy in the formation or bending of the cam projections.

75 I have illustrated the interrupter housing 59 as being riveted to the casing, so that to advance or retard the spark, it is necessary to oscillate the entire timer casing. This oscillation may be effected by a lever 62 secured to the under side of the flange 57 of the casing by the rivets 63 which hold the interrupter housing in position. Other means may be employed for attaching the handle if desired. The casing may be so mounted that oscillation 80 is prevented and the interrupter housing 59 may be mounted to oscillate within the casing. To do this it is merely necessary to make the rivets 63 slightly loose in elongated slots in the wall 57. The rivets 63 may thus connect the interrupter housing and the lever handle 62, and oscillation of the housing in either direction may be effected by the handle 85 without oscillation of the main casing.

90 For delivering the primary or low tension current to the collector ring sections 25 and 26, there are provided a pair of brushes 65 and 66. These are carried by the casing wall at diametrically opposite points, and resiliently pressed against the periphery of the 95 timer head. For supporting the brushes, the cylindrical wall 55 of the casing carries a pair of tubular metal guides 67 which may be rigidly and permanently secured to the casing wall in any suitable manner, as for instance by spinning over the inner ends against the inner surface of the casing wall to grip the latter against beads or flanges on the tubular members 67. Detachably mounted in these 100 tubular guides are a pair of brush holders 68 and 69. Each brush holder has a substantially U shaped spring 70, the free ends or extremities of which extend inwardly and resiliently engage with the upper and lower 105 surfaces of the brush. Between the rear end 110 of the brush and the rear wall of the brush holder is a coil spring 71 pressing the brush endwise toward the timer head. The brush holders are detachably held in place preferably by pins engaging in bayonet slots. Each 115 holder has a pair of pins 72-73 which are of different sizes, or which are positioned at other than diametrically opposite points, so that each holder may be inserted in the tubular guide in only a single position. The pins 120 engage suitable bayonet slots in the guides, as shown in dotted lines in Fig. 1. The pins of one holder may be larger or differently positioned than those of the other, so that the 125 brush holders cannot be interchanged.

At least one of these brush holders, for instance the holder 69, is made of insulation material, and the rear end of the guiding spring 70 is provided with a threaded terminal 74 and lock nuts 75 or other suitable means for the connection of a wire thereto. If the primary circuit be an all wire one, then both brush holders would be constructed as shown at the right hand side of Fig. 1. Preferably the circuit is grounded so that the frame forms a part of the circuit. In this case the brush holder 68 is formed of metal, so as to electrically connect the brush 65 to the metal casing of the timer. With a grounded circuit, it is only necessary to provide one feed wire, which may be connected to the terminal 74. The guiding springs 70 serve to electrically connect the brushes to the brush holder or terminal 74, so that it is not necessary to rely on the coil spring in the rear of the brush as a part of the electric circuit.

The operation of the portions of the apparatus so far described is substantially as follows. With the terminal 74 connected to the battery or to any other suitable source of electrical energy, and with the brush 65 grounded through the metal brush holder 68 to the casing, it will be noted that the two brushes are of opposite polarity. With the parts in the position shown in Fig. 1, the current may flow from the terminal 74 through the brush 68, collector ring section 26, lug 28, and post 32 to contact 30. When the contacts are together, the current may flow from the contact 30 to the engaging contact 31, thence passing through the breaker arm and spring to the post 46, lug 27, collector ring section 25, and brush 65 to the ground, and back to the battery. As the timer head rotates, the circuit will be opened and closed four times during a rotation of the head, and at each breaking of the circuit, the current may jump across the gap between the contacts 30 and 31. After each half revolution of the timer head, the polarity of the collector ring sections 25 and 26 will be reversed, as they will each pass from one brush to the other. Thus for the current breaks during one half revolution of the timer head, the spark or arc will pass in one direction between the terminals 30 and 31, and during the next half revolution it will pass in the opposite direction between these terminals. By this frequent and regular reversal of the polarity of the contacts and reversal of the direction of current flow across the contacts, the pitting of one contact, and the building up of the other contact such as results from uni-directional flow of the sparks or arcs is prevented, as pointed out in connection with my prior Patent No. 1,251,249.

The distributor for the secondary or high tension current includes a casing section or cover 77 which may be formed of insula-

tion material, and detachably secured in any suitable manner. As illustrated, the casing has lugs or shoulders 78 with which spring catches or clips 79 pivoted on the flange 58 may detachably engage. The relative location of the lugs and catches together with a projection or notch 80 in the casing wall insures the securing of the body portion of the casing and the cover together in only a single position. The cover carries an annular row of terminals 81 which may extend through the wall of the cover and be provided with any suitable means for attachment thereto of separate wires leading to the spark plugs. There is also a centrally positioned terminal 82 provided with means for connecting it to the secondary winding of the induction coil. Within the casing there is provided a distributor head 83 which may be formed of insulation material and mounted for rotation with the timer head. This distributor head has a brush 84 for contact with or movement past the several terminals 81, and this brush is connected to a spring contact 85 engaging with the central terminal 82. Thus, as the distributor head 83 rotates it will distribute the current from the terminal 82 to the several terminals 81 in succession. It will of course be understood that the number of terminals 81 corresponds to the number of projections or lugs 61 of the interrupter housing, and that there is a proper relative positioning of these parts to secure the desired current flow. In order to insure the proper positioning of the distributor head in respect to the timer head, and independent of any rotary adjustment of the timer head, on the drive shaft, the distributor head is preferably mounted directly on the timer head, instead of on the shaft. As shown, the distributor head has a socket in its under surface which receives the upstanding end of the sleeve 22 which forms a part of the timer head. The inner end of the socket and the upper end of the sleeve are so formed as to insure proper seating in only a single position, and to insure rotation of the distributor head with the timer head. As shown, one half of the terminal portion of the sleeve is cut away so as to be somewhat shorter than the other half, and to present shoulders engaging with corresponding surfaces in the socket of the distributor head. With this mounting of the distributor head directly on the timer head, it is evident that it is not necessary to exercise any particular caution or care in returning the distributor head to position after it has been removed for any purpose. It will also be noted that the distributor head may be very easily removed so as to give free access to the parts of the timer as it has free slip connections with the tubular part 22.

The construction shown in Fig. 1 is designed for a single ignition system, that is,

one in which there is a single spark plug for each cylinder of the engine, and the number of cylinders corresponds to the number of secondary terminals 81.

As an important feature of my invention, I provide means whereby the construction may be easily and quickly adapted to a double ignition system, that is, one in which there are two spark plugs for each cylinder, and operated simultaneously to give ignition sparks at two separate points in the combustion chamber or working cylinder. For this purpose I provide an auxiliary casing section which may be inserted between the main casing and the cover, and also provide an auxiliary distributor head which may be inserted between the timer head and the distributor head which cooperates with the cover. In Figs. 12 to 16 inclusive I have illustrated my improved construction as provided with these auxiliary or supplementary parts. The auxiliary casing section may be formed of insulation material, and includes a peripheral wall 90 and a transverse wall 91. The wall 90 has its lower edge constructed substantially the same as the lower edge of the cover, so that it may seat on the main casing in place of the cover, and its upper edge is formed similar to the upper edge of the main casing so as to adapt it to receive the main cover of the casing. For the insertion of this auxiliary casing section between the main casing and the cover, no substitution of parts is necessary other than to provide spring clips 79^a in place of the spring clips 79, and of the proper length to extend past the intermediate section and engage with the cover. The peripheral wall 90 of the auxiliary casing section has an annular series of secondary terminals 92 corresponding in number to, and in the same radial planes as the secondary terminals 81 of the cover. These may be similar in all respects to the terminals 81, except that they extend radially rather than parallel to the axes. Their outer portions may be constructed for the attachment of lead wires to the spark plugs in the same way as the terminals 81.

To insure the proper positioning of the auxiliary casing section it is provided with a lug 80^a adapted to enter the recess 80 of the main casing, and its opposite surface is provided with a recess corresponding to the recess 80 and adapted to receive the lug of the cover.

The transverse wall 91 of the auxiliary casing section carries an annular collector ring 93 which may be provided with a transverse slot 94 to prevent circular flow of current therein, and is provided with a lug or flange 95 extending to a binding post or other wire terminal 96 for the attachment of a wire from the secondary winding of the induction coil.

The auxiliary distributor head 98 is provided with a recess in the under side thereof

similar to that in the under side of the main distributor head, and adapting it for direct connection to the timer head. The distributor head 98 carries a brush 99 adapted to engage with or move past the several secondary terminals 92, and is provided with a brush 100 for engagement with the collector ring 93 on the auxiliary casing section. This brush 100 is yieldingly pressed in a direction parallel to the axis of rotation of the device, by means of a spring 101, and is guided in a metal sleeve integral with or electrically connected to the brush 99. Thus the current may be delivered to the collector ring 93 through the terminal 96 and distributed through the brushes 100 and 99 to the several secondary terminals 92. The auxiliary distributor head has an upwardly extending projection or stud 102 corresponding in form to the upper end of the tubular member 22 of the timer head, and adapted to support the main distributor head 83.

With this arrangement the secondary winding of the induction coil may be effectively insulated from the primary winding and the opposite terminals of the secondary may be connected to the two distributor heads. Thus the current flows from the coil through one distributor, and spark plug, the engine frame, another spark plug of the same cylinder, and then through the other distributor back to the coil. Thus two separate sets of spark plugs may be operated simultaneously with a single timer and a single coil, and the parts are so designed that the apparatus may be readily changed so as to adapt it for either a single or a double ignition system, without material change in any of the parts.

The details of construction of the main parts of the timer and distributor, as illustrated in Fig. 12, are substantially the same as the corresponding parts illustrated in Fig. 1, but it will be evident that I may, if desired, manufacture auxiliary casing sections and distributor heads adapted for insertion between the casing body and cover, and between the distributor head and the primary current interrupter of various different forms of construction now on the market. So far as concerns the design of the auxiliary parts for adapting a device to single or double ignition, I do not wish to be limited in any way to the details of construction illustrated in Fig. 1.

In some constructions the current reversing feature may be omitted, and in that event I may use the timer head illustrated in Figs. 17, 18 and 19. In this form, the timer head includes a tubular member 106 having an annular flange or top plate 107. One make-and-break contact 108 may be carried by a flange 109 extending upwardly from an arm 110 insulated from the tubular member 106. The arm 110 is shown as having a central or spider portion 111 clamped to an insulation washer 112 by means of a metal

sleeve 113. The insulation washer projects into the tubular member 106 so that the arm may be swung about the axis of the members 106 and 113 for adjustment of the contact.

6 The two may be clamped rigid in respect to each other by a locking screw 114 extending through a pair of insulation washers 115 and an elongated slot 116 in the plate 107.

The other make-and-break contact 117 may 10 be carried by a depending flange 118 on a bell crank lever 119 serving as a breaker arm.

This arm may have a tubular bearing sleeve 120 rigidly clamped thereto and mounted on a stud 121 extending upwardly from and

15 rigidly secured to the plate 107. The end of the breaker arm opposite to the contact 117 may be bent downwardly to form a flange 122 and the edge of this may be bent around to form walls 123 and 124 directly

20 beneath the plane of the body portion of the arm. Thus there is formed integral with the arm a chamber within which is rigidly secured the projection 125 by means of which the breaker arm is swung to open and close

25 the circuit during the rotation of the head. The contacts may be normally held together by a spring 126 having one end secured to or engaging with the flange or wall 123 and the other end secured to a lug 127 integral

30 with the plate 107 and extending upwardly from one edge thereof. The metal sleeve 113 may form the bearing sleeve adapted to receive and be rigidly secured to the metal drive shaft, so that the ground side of the 35 circuit may be connected to the contact 108. The tubular metal portion 106 may serve as a collector ring, and be engaged by a brush 127 connected to the other terminal of the battery or other source of electrical energy.

40 As one important advantage of the head construction shown in Figs. 17, 18 and 19, it will be noted that all of the metal parts are so designed as to be readily stamped, bent or drawn from sheet metal, and thus may 45 be made and assembled at comparatively small expense. This head, although adapted for use in a timer and distributor, might be employed as the current interrupter of a magneto.

50 Having thus described my invention, what I claim as new and desire to secure by Letters Patent is:—

55 1. A circuit controller for ignition apparatus, including a sheet metal casing, an interrupter head rotatably mounted therein and having a collector ring, said casing having an aperture, and a tubular metal sleeve having an annular bead engaging with the outer surface of the wall of the casing, and an end portion extending through said aperture and expanded into engagement with the inner surface of the wall of the casing, and a brush slidably mounted in said sleeve and engaging with said collector ring.

60 2. A circuit controller for ignition appara-

tus, including an interrupter head having a collector ring, a sheet metal casing enclosing said head and having a tubular metal guide secured to one side thereof, and presenting dissimilar bayonet slots, a brush holder 70 detachably mounted within said guide and having means cooperating with said slots for retaining said holder in a single position, and a brush slidably mounted within said holder and engaging with said collector ring. 75

3. A circuit controller for ignition apparatus, including a shaft, an interrupter head secured thereto and having a collector ring and make-and-break contacts, a bearing for said shaft, a substantially cup shaped sheet 80 metal casing member secured to said bearing, a brush carried by the wall of said casing and engaging with said collector ring, and an annular row of sheet metal projections carried by said casing wall and adapted to 85 effect a relative movement of said make-and-break contacts a plurality of times during each rotation of said head.

4. A combined timer and distributor, including an interrupter head, a sheet metal casing, an annular sheet metal ring rigidly secured to said casing and having a plurality of flanges, and means carried by said head for engaging with said flanges to make and break the circuit as the head rotates. 90

5. A combined timer and distributor, including an interrupter head, a sheet metal casing, a sheet metal ring having flanges integral therewith and extending upwardly therefrom, the body of said ring being rigidly secured to said casing, and a breaker arm carried by said head for engagement with said flanges in succession to make and break the circuit. 100

6. A combined timer and distributor, including an interrupter head, a sheet metal casing having a cup-shaped portion receiving said head and an outwardly extending cover supporting flange, a sheet metal ring secured to said flange for reinforcing the latter and having a plurality of upwardly extending flanges at its inner edge and a breaker arm carried by said head for engaging with said flanges in succession to make and break the primary circuit. 105

7. A combined timer and distributor, including a casing, an annular sheet metal member secured thereto, and having an upwardly extending annular flange at its outer edge and a plurality of separate upwardly extending flanges at its inner edge, a cover engaging with said first mentioned flange, and a breaker arm carried by said head and adapted to engage with said second mentioned flanges in succession. 120

8. A combined timer and distributor including a sheet metal casing having an outwardly extending flange and an upwardly extending flange at the outer edge of the first mentioned flange, an annular sheet metal member se- 125

130

cured to said first mentioned flange and having a flange at its outer edge substantially parallel to the upwardly extending flange of said casing, a cover secured to said casing and engaging with said upwardly extending flanges, and a rotatable member within said casing and having a part adapted to engage with the inner portion of said annular member to effect successive interruptions of the current.

10 9. A combined timer and distributor, including an interrupter head having a breaker arm and an interrupter housing, including an annular sheet metal member presenting a series of upstanding flanges integral therewith and in the path of movement of said arm.

10 10. A combined timer and distributor including a rotatable head having a breaker arm, an interrupter housing including a sheet metal ring presenting upstanding spaced flanges in the path of movement of said breaker arm, and each having its opposite edges curved away from the path of movement of said arm.

10 11. A combined timer and distributor including a rotatable head having a breaker arm, an interrupter housing including a sheet metal ring presenting upstanding spaced flanges in the path of movement of said breaker arm, and each of said flanges being curved transversely to stiffen or reinforce the same and to bring the side edges out of said path.

10 12. A combined timer and distributor including a rotatable head having a breaker arm, an interrupter housing including a sheet metal ring presenting upstanding spaced flanges in the path of movement of said breaker arm, and each of said flanges being curved transversely to stiffen or reinforce the same and to bring the side edges out of said path, and the intermediate portions of the inner surface of each of said flanges being reversely curved and lying in the same circle concentric with said head.

10 13. An interrupter housing for a combined timer and distributor, including an annular sheet metal member having a continuous upstanding flange at its outer edge and a plurality of spaced upstanding flanges at the inner edge.

10 14. An interrupter housing for a combined timer and distributor, including an annular sheet metal member having a continuous upstanding flange at its outer edge and a plurality of spaced upstanding flanges at the inner edge, each of said flanges having its edges curved outwardly and the intermediate portion of the inner surface of the flange curved substantially concentric with the housing.

10 15. A combined timer and distributor, including a head of insulation material, a pair of make-and-break contacts carried thereby, a breaker arm pivoted on said head, a sheet metal casing having a cylindrical peripheral

wall and an annular row of lugs in the path of movement of said breaker arm and disposed at substantially the same radial distance from the center of rotation of said head as said peripheral wall.

10 16. A combined timer and distributor, including a head of insulation material, a pair of make-and-break contacts carried thereby, a breaker arm pivoted on said head, a sheet metal casing having a cylindrical peripheral wall and an annular row of lugs in the path of movement of said breaker arm and disposed at substantially the same radial distance from the center of rotation of said head as said peripheral wall, said head below said breaker arm having collector ring sections separately connected to said contacts, and a brush carried by said peripheral wall for engagement with said collector ring sections.

10 17. An interrupter head for ignition apparatus including a body portion of insulation material, a pair of semi-circular collector ring sections carried thereby, a pivoted arm mounted on said head independently of said sections, a contact carried thereby, a post secured to one of said sections, a contact carried by said post, a spring acting on said arm for normally holding said contacts in predetermined relative positions, and connections between said spring and the other section.

10 18. An interrupter head for an ignition apparatus, including a head having a hole therein, a post mounted in said hole and having a bearing portion eccentric in respect to the part within said hole, a contact carrying member mounted on said head, and a second contact carrying member pivotally mounted on said post, said post being mounted for rotation in said hole, whereby the normal relative position of one contact in respect to the other may be varied.

10 19. An interrupter head for ignition apparatus, including a body portion having a pair of openings therein, a pair of posts rotatably mounted within said openings, a contact carried by one post, a pivoted lever mounted on the other post and having a contact for cooperation with the first mentioned contact, a bearing portion of said last mentioned post being eccentric in respect to the axis of rotation of the post in its opening.

10 20. A combined timer and distributor for double ignition systems, including a rotor having an interrupter head, a distributor head detachably mounted thereon, a second distributor head detachably mounted upon the first distributor head, and a casing having separate series of terminals in operative relationship in respect to the separate distributor heads.

10 21. A combined timer and distributor, including a casing having a body portion, a cover portion adapted to be directly secured thereto, an auxiliary casing portion adapted

- to be secured between said cover portion and said body portion upon the removal of the cover portion, an interrupter head within the body portion, a distributer head detachably connected thereto for cooperation with secondary terminals on the cover section, and an auxiliary distributer head adapted to be inserted between said interrupter head and said first mentioned distributer head upon the removal of the latter, and adapted to cooperate with a series of secondary terminals on said auxiliary casing portion.
22. An attachment for a combined timer and distributer for adapting the same to double ignition, including an auxiliary casing section adapted to be inserted between the body portion and cover portion of the casing of the timer and distributer, and an auxiliary distributer head adapted to be inserted between the interrupter head and distributer head of the timer and distributer.
23. In combination, a casing having a body portion and a cover portion, said cover portion having a series of secondary terminals, a rotor having an interrupter head within said body portion and a distributer head within said cover portion, an intermediate casing section having a series of secondary terminals and adapted to be inserted between the body portion and the cover portion, and an auxiliary distributer head adapted to be inserted between said interrupter head and said first mentioned distributer.
24. A distributer head having a socket in one surface thereof and a projection of corresponding form upon the opposite surface and coaxial therewith, whereby said distributer head may be interposed between a distributer and a rotatable support therefor,
- having cooperating projections and socket engagement.
25. An auxiliary casing section for a combined timer and distributer having a peripheral wall, the upper and lower edges of which are of similar but opposite formation, whereby the casing section may be inserted between a cover and body portion of a timer, and cooperate with the connecting portions of the latter, said casing section having a central aperture therethrough adapted to receive driving connections to a distributer within the cover section.
26. A combined timer and distributer, having a body portion, a pair of superposed detachable casing sections each having a series of secondary terminals, an interrupter head, and a pair of superposed detachable distributer heads for cooperation with the secondary terminals of said superposed casing sections.
27. A combined timer and distributer, including a pair of superposed detachable body sections, each having an annular row of secondary terminals and a feed terminal, the feed terminal of one of said casing sections being upon the end wall thereof, and centrally disposed, and the feed terminal of the other casing section being upon the peripheral wall, an annular conductor secured to the end wall of the last mentioned casing section, and to said last mentioned feed terminal, and a pair of distributer heads each having brush bearings for connecting the feed terminal of its corresponding section to the several secondary terminals thereof.

Signed at New York, in the county of New York and State of New York, this 21 day of February, A. D. 1922.

JOSEPH H. LEHMAN.
